UNITED STATES PATENT OFFICE

FRANCIS T. ROBINSON, OF ROCKVILLE CENTER, NEW YORK, ASSIGNOR TO ARKELL
SAFETY BAG COMPANY, OF NEW YORK, N. Y., A CORPORATION OF NEW YORK

LINING BAG AND METHOD OF PRODUCING THE SAME

Application filed July 25, 1928. Serial No. 295,163.

My invention relates to a folded bag and method of producing the same and has for its object to produce a bag folded so as to have re-entrant lower corners and adapted 5 to be used as a lining for a container, the same being in convenient form for packing, shipping and storage. It also has for its object to produce such a bag which can be ballooned into substantially the shape of the container to be lined. It also has for its object 10 to provide a method for producing such bag. The following is a description of a bag embodying my invention and the method of producing the same, reference being had to the accompanying drawings, in which,

Fig. 1 shows a side elevation of a bag before it is folded so as to embody my invention;

Figs. 2 and 3 show the first step of the 20 method as applied to such bag for forming it into a liner for a circular container such as a barrel;

Fig. 4 shows the second step;

Fig. 5 shows the next two steps;

Fig. 6 is a bottom plan view of the partially 25 folded bag shown in Fig. 5;

Fig. 7 is a section on the line 7—7, Fig. 6;

Fig. 8 shows the next step; and

Fig. 9 shows an end elevation of the resulting bag embodying my invention;

Fig. 10 shows the first step of folding the bag when used as a liner for a rectangular container; while

Fig. 11 shows the next step in folding the 35 lining, the remaining steps being similar to those for forming the tubular container lining.

In carrying out my improved method I use the apparatus shown and described in my 40 Patent No. 1,508,125, dated September 9, 1924, the same consisting of a horizontal cross member 2 to which are pivoted semi-circular spreader leaves 4, means being provided as shown in said patent for moving said leaves 45 from a somewhat vertical position, as shown in Fig. 3, to a horizontal position as shown in Fig. 5, and vice versa.

My improved lining is of the type described and claimed in my Patent No. 1,624,626, dated

50 April 12, 1927.

In forming my lining I first form a bag having a side seam 6 and a bottom seam 8, as shown in Fig. 1, the bag being preferably made of a longitudinally crinkled kraft paper or the like. I then place the bag over the 55 former with the seam 8 above and parallel to the cross member 2. I then tuck the end portions 12 of the seam between the two leaves 4 of the former, as shown in Fig. 4, so that these end portions are within the 60 body of the bag and lie beneath the intermediate portion 10 of the seam 8. I then bring the leaves 4 into horizontal position, as shown in Fig. 5, which action spreads the bottom of the bag and draws the portion 10 65 down toward the cross member with the in-turned ends of the seam and portions adjacent thereto beneath the portion 10 and portions adjacent thereto. This is shown in Fig. 6. I then by hand pressure form a 70 crease around the periphery of the leaves 4, this crease, when the leaves are extended, conforming to the shape of the container to be lined. Thus, when a container is a circular container and the former has semi-circular leaves, this crease will be a circular 75 crease. I then hold the central portion 10 of the seam down in proximity to the cross member 2 and raise the members 4 into approximately vertical position, thus forming 80 a re-entrant fold in the bottom of the bag. I then lift the bag thus folded off of the former and still further collapse it so as to bring the opposing faces of the re-entrant folded portion together, as shown in Fig. 9, whereupon 85 the bag is ready for packing for storage or shipment.

The bag thus formed has the side walls of its body portion in alinement with the bottom seam salient, as shown at 14, and when 90 it is grasped by one side of the mouth can be ballooned or filled with air so as to substantially conform to the interior dimensions of the container to be lined. When the bag is so ballooned the in-turned ends of the seam 95 8 and portions adjacent thereto are held beneath the seam portion 10 and portions adjacent thereto, as shown in Fig. 6, so that in the ballooning process the bottom of the bag is only partially unfolded.

In forming a lining for a rectangular container I make the leaves of the container rectangular and after the bag bottom has been extended thereon, as shown in Fig. 10, I tuck the end portions 12 of the bottom seam 8 beneath the intermediate bottom portions, as shown in Fig. 11, and then crease the bag along the periphery of the rectangular extended former. I then collapse the former while holding the intermediate portion of the bottom seam down so as to form the re-entrant portion, substantially as shown in Fig. 8, and after removing the bag from the former further collapse the reentrant portion.

In finally preparing the lining for shipment, instead of forming the re-entrant fold in the lining, as above described, the bottom of the bag may be folded over, as illustrated and described in my said Patent No. 1,624,626.

By folding the bag as above described, I secure a commercial article of manufacture having withdrawable portions of its bottom seam and portions adjacent thereto held beneath intermediate portions of said seam and adjacent portions so as not to be unfolded when the bag is ballooned, and further have the article so folded as to be in form for packing for storage and shipping.

As will be evident to those skilled in the art, my invention permits of various modifications without departing from the spirit thereof or the scope of the appended claims.

What I claim is:

1. A bag having a preformed bottom suitable for lining containers comprising a bag tube closed by a seam at one end with the ends of the seam tucked inwardly so as to be within said bag and overlie the inner sides of intermediate portions of said seam, the bottom of the bag thus formed being creased along a line conforming to the shape of the container to be lined preliminary to the insertion of the bag in the container.

2. A bag having a preformed bottom suitable for lining containers comprising a bag tube closed by a seam at one end with the ends of the seam tucked inwardly so as to be within said bag and overlie the inner sides of intermediate portions of said seam, the bottom of the bag being creased along semi-circular lines conforming to the shape of a circular container to be lined therewith preliminary to the insertion of the bag in the container.

3. The method of producing a lining having a preformed bottom for a container which comprises forming a bag tube with one end of the tube closed by a seam, tucking the ends of the seam inwardly toward the axis of the tube so as to lie within the bag and overlie the inner sides of intermediate portions of said seam, and preliminary to the insertion of the bag in the container creasing said bag ad-

jacent to its bottom portion along a line conforming to the shape of the container to be lined when said bottom portion is flattened.

4. The method of producing a lining having a preformed bottom for a container which comprises forming a bag tube with a seam closing one end, tucking the ends of the seam inwardly toward the axis of the bag so as to lie within the bag and overlie the inner sides of intermediate portions of said seam, and preliminary to the insertion of the bag in the container creasing said bag adjacent to its bottom portion along semi-circular lines conforming to the shape of a circular container to be lined.

In testimony whereof, I have signed my name to this specification this 24th day of July, 1928.

FRANCIS T. ROBINSON.
